UNITED STATES PATENT OFFICE.

HEINRICH GAENSSLLEN AND GOTTHILF GAENSSLLEN, OF ESSLINGEN,
WÜRTEMBERG, GERMANY.

ROTARY JEWEL.

SPECIFICATION forming part of Letters Patent No. 340,108, dated April 20, 1886.

Application filed July 25, 1885. Serial No. 172,627. (No model.)

To all whom it may concern:

Be it known that we, HEINRICH GAENSSLLEN and GOTTHILF GAENSSLLEN, both citizens of Germany, residing at Esslingen, in the Kingdom of Würtemberg, Germany, have invented 5 certain new and useful Improvements in Rotary Jewels, of which the following is a specification.

Our invention relates to rotary jewels, 10 adapted for cravats and similar articles of wearing-apparel.

Our invention consists of ornaments mounted on the main arbor of a watch mechanism, similar to the hands of a dial thereof, whereby 15 one ornament may be made to rotate in one direction, while the other rotates in direct opposition thereto, thus presenting a very beautiful optical illusion.

In the accompanying drawings, Figure 1 20 represents a cravat upon which are shown two stars which are driven by watch mechanism held within the frame shown by dotted lines. Fig. 2 is a side elevation of the frame, showing the mechanism connected therewith. Fig. 25 3 is a view of the front plate, which also shows the mechanism connected in part to the back plate. Fig. 4 shows the mechanism under the front plate.

Similar letters of reference indicate similar 30 parts throughout the drawings, in which—

a represents the barrel-wheel, provided with a projected draw-pivot, *Z*, which of course carries a fly-wheel. The teeth of the barrel-wheel *a* mesh into those of the spring-wheel *b*. 35 On the arbor of the latter is mounted the wheel *c*. The teeth of the latter mesh into those of the spring-wheel *d*, mounted on the same arbor with that of *e*, the latter of which engages with the toothed wheel mounted on the arbor carrying the escapement-wheel *g*, which is in junction with the escapement, being located in the space *R*.

Instead of using any escapement, some other wheels which end with a fly or balance wheel 45 may be used, in order to effect a noiseless action.

In Fig. 4 will be shown the mechanism located beneath the plate *H*. The wheel *h* is fixed on the prolonged portion of the arbor

carrying the spring-wheel *d*, which meshes 50 into both the toothed wheels *i* and *m*. On the pivot of the spring-wheel *m*, which is prolonged outward and bearing upon a small bridge, *v*, is a casing-tube, which is the bed for the spring-wheel *n'*, and over which is set the 55 wheel *n* by means of a leading tube. On the arbor carrying the spring-wheel *i* is to be found the fixed wheel *k*, which meshes into wheel *n*. It will be observed that the front star, *q*, which is composed of eight points, will 60 rotate to the right, while the rear star, *s*, composed of sixteen points, will rotate to the left.

In Fig. 5 is shown a modification. *W* and *X* will be allowed to turn in two pivots, on which is fixed the complement *p* by a pin, *p'*. 65 This pin extends to the eccentric *r*, which is fastened on the pivot *m'* of the spring-wheel *m* of Figs. 3 and 4. On this object *W* is placed a square pin, *u*, adapted to enter the casing *t*, which is fixed upon the cylinder. This arrangement allows the moving figure to be less dependent on the works, as if figures to be moved were put directly on the complement of the spring-wheel.

Having thus described our invention, what 75 we claim as new, and desire to secure by Letters Patent, is—

1. In jewelry, the combination consisting of the jewels mounted upon arbors, one within the other, the arbors adapted to be rotated in 80 opposite directions by watch or clock mechanism.

2. In jewelry, the combination consisting of the barrel-wheel *a*, draw-pivot *Z*, spring-wheel *b*, wheel *c*, spring-wheel *d*, wheel *e*, escape- 85 ment-wheel *g*, plates *H* and *o*, wheel *h*, wheels *i* *m*, bridge *v*, spring-wheel *n'*, wheel *n*, fixed wheel *k*, and stars *q* and *s*, the whole forming a complete device, substantially as shown and described.

In testimony whereof we hereunto sign our names, in the presence of two subscribing witnesses, this 18th day of May, 1885.

HEINRICH GAENSSLLEN.
GOTTHILF GAENSSLLEN.
